Primary Examiner — Michael A. Pratt

(57) **CLAIM**

The ornamental design for an eyepiece of an optical sight as shown and described.

DESCRIPTION

FIG. 1 is a top view of an eyepiece of an optical sight according to this disclosure;

FIGS. 2 and 3 are side views thereof;

FIG. 4 is a bottom view thereof;

FIGS. 5 and 6 are end views thereof;

FIG. 7 is a top perspective view thereof; and,

FIG. 8 is a bottom perspective view thereof.

Mirror images of the eyepiece of the optical sight are within the scope of the claimed design.

Broken lines in the drawings show environmental or optional structures and form no part of the design to be patented.

1 Claim, 7 Drawing Sheets(56)
